EMBORESSED PLASTIC SHEET OR SIMILAR ARTICLE

William M. Feder, New York, N. Y.

Application September 14, 1951, Serial No. 16,643

Term of patent 7 years

(Cl. D87—3)

To all whom it may concern:

Be it known that I, William M. Feder, a citizen of United States, residing at New York city, in the county of New York and State of New York, have invented a new, original, and ornamental Design for Embossed Plastic as Sheet or Similar Article, of which the following is a specification, reference being had to the accompanying drawing, forming part thereof.

Fig. 1 is a plan view of an embossed plastic sheet or similar article showing my new design; while

Fig. 2 is a cross-sectional view taken along line 2—2 of Fig. 1.

I claim:

The ornamental design for an embossed plastic sheet or similar article, as shown.

WILLIAM M. FEDER.
